CLAIM

The ornamental design for a beverage machine with display screen, as shown and described.

DESCRIPTION

FIG. 1 is a top, front, right side perspective view of a beverage machine with display screen;

FIG. 2 is top, front, left side perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The short dash-long dash broken lines illustrate boundaries of the claimed design and form no part of the claimed design. The dash-dash broken lines illustrate portions of the beverage dispenser that form no part of the claimed design.

1 Claim, 7 Drawing Sheets
